Inventor:
Alexander Laurie
By his Attorney
James F. Williamson

UNITED STATES PATENT OFFICE.

ALEXANDER LAURIE, OF CARROLL, NEBRASKA.

PIG-DELIVERY FORCEPS.

Application filed April 16, 1923. Serial No. 632,305.

To all whom it may concern:

Be it known that I, ALEXANDER LAURIE, a citizen of the United States, residing at Carroll, in the county of Wayne and State 5 of Nebraska, have invented certain new and useful Improvements in Pig-Delivery Forceps; and I do hereby declare the following to be a full, clear, and exact description of the invention, such as will enable others skilled in the art to which it appertains to make and use the same.

This invention relates to obstetrical forceps and particularly to such forceps designed for use with animals, particularly 15 swine. A great many sows are lost as well as a great number of young pigs, owing to the sow having difficulty in delivering the pigs. Under normal and correct conditions the pigs are presented for delivery head 20 first, but they frequently turn in various ways in the vaginal duct and it is necessary to use instruments to deliver them. Unless the proper instruments are used and carefully used the tissues of the sow will be 25 lacerated and torn and the young pigs crushed and their bones broken. The safest and best place to engage the young pig is by the jaw if it is presented head first for delivery, or around one or both legs if it is 30 presented, hind end first for delivery.

It is an object of this invention, therefore, to provide a pair of forceps having a flat means adapted to engage under the tongue in the mouth of the young pig and co-operating means engaging under the jaw of the 35 pig.

It is a further object of the invention to provide such a pair of forceps having means on one of the handles thereof adapted to 40 turn the pig about the longitudinal axis of its body in the vaginal duct of the sow.

It is more specifically an object of the invention to provide a pair of forceps having a flat blade with rounded ends as one of its jaws and a co-operating hook as the other jaw which is bent toward said blade and disposed at the end thereof.

These and other objects and advantages 50 of the invention will be fully set forth in the following description made in connection with the accompanying drawings in which like reference characters refer to the same parts throughout the different views, in which

Fig. 1 is a view in side elevation of the 55 forceps; and

Fig. 2 is a view in front elevation of the major portion thereof, as seen from the right of Fig. 1.

Referring to the drawings, the device 60 comprises the handle portions 1 and 2 of considerable length which may be of any desired form, but which are shown as made of cylindrical rods. The handle portion 2 is flattened as at 3 adjacent one end and apertured to receive the pivot bolt or rivet 4 and the handle 1 has a similar flattened portion 5, the portions 3 and 5 being in contact and connected by the said pivot. The handle 2 has its jaw portion formed as a 70 flat tongue or blade 6 having its widest part adjacent its outer end, which end is nicely rounded at the edges. Said blade tapers in width inwardly and while the same may be of uniform thickness, it is illustrated as having a slight taper in thickness toward its outer end. The outer portion of the jaw on the handle portion 1 is also of cylindrical 75 shape and formed with a short hook portion 7 which is bent toward the blade 6 and has its end rounded and normally disposed beyond the end of the blade 6. It will be noted that the portion 7, as clearly shown in Fig. 1, is disposed outward beyond the end 80 of the plate or blade 6. The handle portion 2 has at its outer or other end, a laterally bent portion 8, the end of which is normally rounded, said portion being cylindrical so that the whole end presents only curved smooth rounded surfaces. The 85 end of the handle portion 1 is also bent outwardly to form a hook 9, the end of which is pointed.

As previously stated, the pigs properly 90 should be presented for delivery head first. The vaginal duct of the sow is generally circular in shape and as the pigs approach the delivery opening they should be on their bellies. It frequently happens, however, 95 that the pigs approach the opening disposed on their backs and in this position, delivery is exceedingly difficult as the pig will pass the delivery opening and the crown of its head will be in the adjacent bone of the sow. The hook or bent portion 8 of the end portion 100 2 has been found to be exceedingly efficient for insertion into the vaginal duct 105 for turning the pigs laterally, or turning

the same on the longitudinal axis of the body so that the pig will be disposed on its belly. The pig's nose will then start through the opening. If the pig is presented head first for delivery, the forceps are held by the handles 1 and 2 and the jaws 6 and 7 inserted into the sow. The blade 6 is manipulated to be positioned in the mouth of the pig and under the tongue so that the tongue will not be cut or injured. The under jaw bone of the pig is V-shaped and the jaw 7 of the forceps will be disposed under this lower jaw of the pig and in the recess of said bone. The portion 7 is disposed outwardly beyond the blade 6 on account of the fact that the pig's tongue is attached to the lower jaw in front of the fork of the jaw or the jaw bone. The hook 7 therefore must extend far enough so that it will hook into the jaw bone before the blade 6 presses against and injures the cord under the tongue. The inner surface of the blade 6 at its base curves into handle 3 to form an arch or concavity, as clearly shown in Fig. 1, to provide room for the pig's teeth so that the teeth will not be crushed. With the pig so engaged the same can be withdrawn and delivered without injury thereto and without injury to the sow. If the pig is presented rear end foremost, one or both of the legs of the pig can be engaged between the jaw 7 and blade 6 and a tight hold on the legs secured. The pig can then be drawn out and delivered without injury. The pointed hook 9 on the handle 1 is not novel and is somewhat like the common implement or hook often used by farmers or veterinarians for assisting in the delivery of the pigs when, as a last resort, it is desired only to get the pigs away whether dead or not. Such a hook, however, is unsuitable to be inserted far into the vaginal duct, as when this is done the sow is seriously injured.

From the above description it is seen that applicant has provided a simple and very efficient tool for the purpose intended. The smooth round hook portion 8, while quite simple in construction, has been found to be very efficient in turning over the pigs, as described. The formation of the jaws of the forceps has also proven exceedingly efficient in practice. The tool has actually been made and used and the successful operation thereof fully demonstrated.

It will, of course, be understood that various changes may be made in the form, de-

tails and proportions of the parts without departing from the scope of applicant's invention, which, generally stated, consists in a device capable of carrying out the objects above enumerated, such as shown and described and as set forth in the appended claims.

What is claimed is:

1. A pig delivery forceps having in combination, means for engaging the inside of the lower jaw of an undelivered pig beneath the tongue thereof, and an opposed blunt means pivoted to said first mentioned means and disposed centrally transversely thereof for engaging the exterior of said lower jaw between the sides thereof. 60

2. A pig delivery forceps having in combination, pivotally opposed members, one forming a blade tapering to a thin edge for engaging the inside of the lower jaw of the pig beneath the tongue and the other member formed as a blunt ended rod disposed centrally transversely of said blade and directed substantially at right angles thereto beyond the outer end thereof for engaging the pig at the exterior of the lower jaw and between the jaw bones. 70

3. A forceps for delivering pigs and other animals, comprising two arms pivoted together, the grasping end of one of said arms being formed as a blunt-ended hook, the grasping end of the other of said arms being formed as a substantially flat thin blade, the outer end thereof being rounded and of greater width than the remainder of said blade, said blade being adapted to fit beneath the tongue of an undelivered pig, said hook end being positioned upwards and away from the outer end of said blade, whereby, when the blade member is inserted beneath a pig's tongue, the hook member may be made to grasp immediately behind the under jaw bone of the pig and a firm hold may be obtained by the co-operation of the forceps arms without injuring the pig. 80

4. A forceps for delivering pigs and other animals, comprising a pair of jaws, one of which is in the form of a thin narrow blade having a rounded end and the other of which is in the form of a hook bent toward said blade and having a blunt end disposed outwardly of the end of said blade, said blade tapering in width from its outer end inwardly. 90

In testimony whereof I affix my signature.
ALEXANDER LAURIE.
